DUSTING TOOL KIT FOR SUCTION
CLEANERS

William H. Kitto, Greentown, Ohio, assignor to
The Hoover Company, North Canton, Ohio, a
corporation of Ohio

Application April 20, 1942, Serial No. 439,702

3 Claims. (Cl. 206—16)

The present invention relates to a tool case for cleaning tools employed with suction cleaners.

An object of the invention is to provide a new and improved kit for suction cleaning tools. A further object is to provide a tool kit which is self-supporting in an erect position. Another object is to provide a kit having an enlarged base to support the kit in erect position and also to engage the tools therein at spaced points to provide multiple lateral supports for the tools. Other objects and advantages of the invention will be apparent from the following description and attached drawings, wherein:

Figure 1 is a front elevation of the tool kit suspended from a door knob;

Figure 2 is a perspective view of a member for supporting the tools laterally and forming part of the base of the tool kit;

Figure 3 is a perspective view of the blank forming the base of the tool kit, and the lateral tool supporting member arranged for assembly in the base;

Figure 4 is a perspective view of the base partially folded prior to assembly on the panel of the tool kit;

Figure 5 is a perspective view of the base during assembly to the panel of the tool kit, and

Figure 6 is a perspective view partly in section of the assembled tool kit.

The embodiment of the invention disclosed herein comprises a tool kit 10 having a panel 11 and a base 12 including a lateral tool supporting member 13. The panel 11 is formed of relatively stiff cardboard or fibreboard or the like, and includes an insert 14 of stiff material which extends throughout the height of the tool kit and an exterior fibreboard cover 15 which forms front and rear walls 16 and 17, respectively, covering the panel insert 14. A flap 20 is provided on the panel cover 15 and is folded over the top edge of the panel insert 14 and is secured to the latter by fastening means such as staples 21. Attached to the panel covering 15 by means of staples 22 are tool holders 23, 24 and 25, the holders 23 and 24 supporting the upper ends of the tools 26 and 27, while the holder 25 supports a brush 28. Each of these holders is formed of fibreboard 29 and the ends 30 are passed through slots in the panel cover front wall 15 and folded over along the interior surface thereof and these ends are then attached to the panel covering 15 by the staples 22. The bight portion of each holder is spaced from the panel cover 15 and cooperates with the latter to provide an opening into which the tools 26, 27 and 28 are inserted. The upper end 34 of

the fibreboard forming the holder 25 is provided with diametrically opposed recesses 35 which receive the transverse portion 36 of the brush 28 to hold the transverse portion 36 spaced away from the panel cover 15 and thereby tilt the brush 28 downwardly and rearwardly towards the panel cover 15 whereby the lower end of the brush abuts the cover 15, and the recesses 35 also prevent rotation of the brush 28 in the holder 25.

10 The lateral tool supporting member 13 forming part of the base 12 is formed from a blank 39 of relatively rigid fibreboard and is folded along lines 40, 41 and 42 to form a triangular cross-section 43 defined by walls 44, 45 and 46, while a flat bottom wall 47 extends rearwardly from the apex 48 of the triangular section 43 and is provided with openings 38 and 50 for a purpose hereinafter described. Prior to folding the blank 39 along the line 41, four cut-outs 49 are formed therein and upon folding the blank along the line 41, the cut-outs 49 form aligned openings 51 disposed in the walls 44 and 45 to receive the lower ends of the cleaning tools 26, 27, 52 and 53. The wall 44 is downwardly and forwardly inclined with respect to the top wall 45 whereby the defining edges of the openings 51 in the walls 44 and 45 engage the lower extremities of the cleaning tools 26, 27, 52 and 53 at spaced points to provide a plurality of lateral supports for the tools at spaced points.

15 The base 12 is formed from a blank 55 of relatively rigid fibreboard and is cut to form two pairs of flaps 56, 56 and 57, 57 and is creased at 58, 59, 60, 61 and 62 to form walls 63, 64, 65, 66, 67 and 68, and provided in the wall 65 are four openings 70 formed by hinged tabs 71.

20 In order to assemble the base 12 and the lateral tool supporting member 13, the apex 69 of the latter is placed against the crease 59 in the base 12, and the edge of the lower wall 47 of the member 13 is placed against the crease 58 and thereafter the wall 65 is folded along the crease 59 to lie contiguous with the wall 45 of the member 13. In this position the tabs 71 formed in providing openings 70 are folded along the crease 59 through the openings 51 so as to be contiguous with the wall 64 of the base, and the openings 70 are in register with the openings 51. Thereafter the wall 66 is folded along the crease 60 to lie adjacent the wall 46 of the triangular section 43 and the flaps 57 folded along their creases 72 to close the open ends of the member 13, the flaps 56 are folded at their creases 73 with their lips 74 and 75 inserted between the walls 64, 45 and 68, 47, respectively. The flaps 56

and 57 are secured together by staples 17 to hold the base 12 in the form of a parallelogram and to retain the member 13 therein.

The base 12 is attached to the panel 11 by folding the wall 68 along the crease 62 to lie along the rear surface of the panel and is secured to the latter by staples 78. The base 12 is additionally fastened to the panel 11 by means of staples 79 extending through the tabs 71, wall 64 and panel 11.

A handle 80 is provided at the upper end of the panel 11 and comprises a pair of flexible straps 81 and 82 having their opposite ends attached together as at 83 and are secured to the rear wall 17 of the panel cover 15 by means of staples 35. The straps are arranged side by side and when separated a dusting tool hose 86 may be inserted therebetween, and with the straps suspended from a door knob 87 or other type of hook, will support the hose 86 and also suspend the kit, as shown in Figure 1.

In use, the tool kit is placed upon the floor and the base supports the kit in an upright position without other external support. The hose 86 is removed and one end connected to the suction cleaner and the desired cleaning tool is removed from the kit and attached to the opposite end of the hose 86. It will be noted that the tools 26 and 27 have their lower ends supported in the base 12 and their upper ends in holders 23 and 24, respectively. The tools 52 and 53 are supported solely by the base 12 and due to the spaced walls 44 and 45 in the base, the tools are supported laterally at a plurality of spaced points to prevent the tools from tilting sidewise in the openings 51. The tools 52 and 53 have their extreme lower ends resting on the wall 63 of the base 12 and are disposed in the openings 38 and 50, respectively, in the bottom wall of the member 13.

I claim:

1. A tool case for suction cleaning tools comprising a body of relatively rigid material including a panel and an enlarged base projecting forwardly of said panel to support the latter in erect position, a member of relatively rigid material 45

attached to said panel and having a portion spaced from the latter to form therewith a tool holder, oppositely disposed recesses along the upper marginal edge of said member and spaced from said panel, said recesses receiving a tool to space the latter from said panel, said recesses and member cooperating to tilt the lower end of said tool downwardly and inwardly toward said panel, whereby the lower end of said tool rests against said panel and the upper end of said tool in said recesses is spaced from said panel.

2. A tool case for suction cleaning tools comprising a body of relatively rigid material including a panel and an enlarged base projecting forwardly of said panel to support the latter in erect position, a member forming part of said base and folded to provide a front wall spaced from said panel, a top wall between said front wall and panel, and a wall inclined with respect to said top wall, a cut-out extending across the crease between said top wall and inclined wall to provide spaced aligned openings therein for the reception of a tool, the defining edges of said spaced aligned openings engaging the tool at vertically spaced points to provide multiple lateral supports for the tools at intervals therealong to position said tool adjacent said panel above said enlarged base.

3. A tool case for suction cleaning tools comprising a body of relatively rigid material including a panel and an enlarged base projecting forwardly of said panel to support the latter in erect position, a member forming part of said base and folded to provide a front wall spaced from said panel, a top wall between said front wall and panel, and a wall inclined with respect to said top wall, aligned openings in said top wall and inclined wall, the defining edges of said spaced aligned openings engaging the tool at vertically spaced points to provide multiple lateral supports for the tools at intervals therealong to position said tool adjacent said panel above said enlarged base.

WILLIAM H. KITTO.
